UNITED STATES PATENT OFFICE.

ALBERT H. TAYLOR, OF EASTON, PENNSYLVANIA, ASSIGNOR, TO INGERSOLL-RAND COMPANY, OF NEW YORK, N. Y., A CORPORATION OF NEW JERSEY.

WATER-SPRAYING DEVICE FOR PNEUMATIC TOOLS.

No. 905,388.

Specification of Letters Patent. Patented Dec. 1, 1908.

Application filed February 21, 1908. Serial No. 416,973.

To all whom it may concern:

Be it known that I, ALBERT H. TAYLOR, a citizen of the United States, and resident of Easton, in the county of Northampton and State of Pennsylvania, have invented a new and useful Improvement in Water-Spraying Devices for Pneumatic Tools, of which the following is a specification.

My invention relates to a water spraying device for use in connection with pneumatic tools and it is directed more particularly to a water spraying device for use in connection with hammer drills, where it is desirable that the dust which is cut by the drill steel, should be laid by coming in contact with the spray of water, as the dust leaves the hole being bored.

In ordinary practice where air is used to clean the hole being bored, the dust is blown out of the hole and mixes with the atmosphere, thus rendering the air unfit for breathing and dangerous for the operator, especially so in closed workings, such as mines and tunnels.

The object of my invention is to provide an ejector which is connected to a water supply and to the exhaust air from the tool, whereby a jet of air issuing from the force nozzle of the ejector will draw water from the water supply and force it through the discharge nozzle of the ejector in the form of a spray of water which may be directed against the mouth of the hole being bored, thus dampening the dust particles before they have time to mix with the air and causing the particles to be precipitated.

A practical embodiment of my invention is represented in the accompanying drawings in which—

Figure 1 is a view in side elevation, showing a hand pneumatic tool of the hammer drill type with my water spraying device applied thereto, the parts being shown in position as in use, Fig. 2 is a detail longitudinal central section on an enlarged scale, through the tool and rotating handle, Fig. 3 is a transverse section taken in the plane of the line A—A of Fig. 2, looking in the direction of the arrows, and Fig. 4 is a transverse section taken in the plane of the line B—B of Fig. 2, looking in the direction of the arrows.

The water spraying device is herein shown as applied to a hammer drill of the well known axial valve type.

The tool handle is denoted by 1, the cylinder or barrel, by 2; the drill steel by 3 and the rotating handle by 4, 5. The air supply pipe 6 leads to the tool handle 1, from any suitable source of supply, not shown herein.

60

A pipe 7 leads from a source of water supply, such, for instance, as a tub or cask 8, to the outer end of the member 5 of the rotating handle, which member is made hollow to provide a water supply chamber 9. The cylinder or barrel 2 of the tool is provided with one or more air exhaust ports 10. The members 4 and 5 of the rotating handle have formed therein an annular air supply chamber 11 in communication with the air exhaust ports 10 of the tool. The ejector, carried by the hollow rotating handle, comprises a discharge nozzle 12 in communication with the water supply chamber 9, and a force nozzle 13 in communication with the air supply chamber 11, through a passage 14.

65

When the tool is in operation, a jet of exhaust air from the tool is directed from the force nozzle 13 into the discharge nozzle 12 of the ejector, for lifting the water from its source of supply and forcing it through the discharge nozzle, so that it issues therefrom in the form of spray which is so directed as to strike the desired spot.

70

While I have shown my invention in connection with a hammer drill, it is to be understood that I contemplate utilizing the same wherever it may be desirable for use.

80

What I claim is:

1. A water spraying device for pneumatic tools comprising a rotating handle and an ejector carried thereby in communication with a water supply and the exhaust air from the tool for spraying the water onto the desired spot.

85

2. A water spraying device for pneumatic tools, comprising a hollow rotating handle and an ejector carried thereby in communication with a water supply and the exhaust air from the tool, for spraying the water on to the desired spot.

90

3. A water spraying device for pneumatic tools, comprising a hollow rotating handle and an ejector carried thereby, for spraying water on to the desired spot, said handle having a water supply chamber therein in communication with the discharge nozzle of the ejector and an air supply chamber therein in communication with the exhaust port of the tool and the force nozzle of the ejector.

95

100

105

110

4. A pneumatic tool comprising a tool handle, an air supply pipe leading thereto, a cylinder having an exhaust port, a hollow rotating handle carried by the cylinder, an ejector carried by the handle for spraying water on to the desired spot, said handle having an air supply chamber therein in communication with the exhaust port and force nozzle of the ejector, and a water supply chamber therein in communication with the discharge nozzle of the ejector, and a

water supply pipe leading to said water supply chamber in the rotating handle.

In testimony, that I claim the foregoing as my invention, I have signed my name in presence of two witnesses, this 19th day of February 1908.

ALBERT H. TAYLOR.
